SHIELD PANTY

Edward R. Sutter, Chicago, Ill., assignor to Beau-T-Form Foundations, Inc., a corporation of Illinois

Application July 30, 1949, Serial No. 107,804

7 Claims. (Cl. 128—149)

1

This invention relates to a detachable shield pantie for a foundation garment and has as a general object to provide a new and improved shield pantie of the character described.

A more particular object of this invention is to provide a shield having a divided rear portion which may yield laterally of the shield to relieve stresses normally occurring in the shield such as those produced when the wearer bends forwardly from the waist or assumes a sitting position.

Another object is to provide a shield having a yieldable rear portion which remains flat in all relative positions of the yieldable portions.

Another object is to provide a shield having a pair of superposed central strips of material divided at their rear portions to provide laterally yielding portions of the shield for the comfort of the wearer.

A further object is to provide a shield having a laterally yieldable rear portion comprising separate overlapping tabs formed by folding the rear portions of central pieces of material in a particular manner.

Other objects and advantages will become apparent from the following description taken in connection with the accompanying drawing, in which:

Fig. 1 is a perspective view of a shield embodying the features of this invention and illustrated in the position it assumes on the wearer;

Fig. 2 is a partial plan view of the rear portion of the shield illustrating in dotted lines the parts thereof in laterally spread position;

Fig. 3 is a sectional view taken along line 3—3 of Fig. 1;

Fig. 4 is a transverse sectional view taken approximately along the line 4—4 of Fig. 1;

Fig. 5 is a transverse sectional view taken approximately along the line 5—5 of Fig. 1.

While the invention is susceptible of various modifications and alternative constructions, it is here shown and will hereinafter be described in a preferred embodiment. It is not intended, however, that the invention be limited thereby to the specific disclosure made but on the contrary it is intended to cover all modifications and alternative constructions falling within the spirit and scope of this invention as defined in the appended claims.

As shown herein for purposes of disclosure, the shield comprises generally a main or central piece, generally designated 10, a divided rear portion of the central piece or rear portion of the shield, means for detachably securing the shield

2

to the front and rear of a foundation garment and chafe preventing portions, generally designated 11. The central piece 10 is shaped to conform to the space between the legs to have the shield fit smoothly and comfortably and prevent folds of excess material which would itself chafe the wearer. The chafe preventing portions 11 are attached to either side of the central piece and depend between the thighs of the wearer to prevent contact and chafing between the flesh of the thighs.

The central piece 10 is constructed of an upper strip 12 and a lower strip 13 of material as best seen in the cross-sectional view of Fig. 5. The marginal edges of the strips 12 and 13 are in registry from the front 14 of the shield to a point indicated at 15 in Fig. 1. From the point 15 to the rear of the superposed strips 12 and 13, each strip is folded upon itself to form separate tabs 21 and 26. The upper strip 12 is folded on a bias 16 with the folded portion 17 positioned under the upwardly exposed surface of the strip 12. As best seen in Figs. 4 and 5, one edge 18 of the folded portion 17 is aligned with the marginal edge of the strip 12 and the other or free edge 19 of the folded portion 17 extends across the strip 12 between the marginal edges thereof. Textile stitching 20 binds the upper and lower central strips 12 and 13 together and also binds the edge 18 of the folded portion 17 to the marginal edge of the strip 12. The folded end portion of the strip 12 thus forms the tab 21 which is part of the rear support for the shield as hereinafter described.

The lower central strip 13 is folded, in a manner similar to that described above for the strip 12, at its rear portion on a bias 22 which crosses the bias 16. The folded portion 23 of the strip 13 is positioned above the strip 12 as best seen in Fig. 4. One edge 24 of the folded portion 23 is aligned with the marginal edge of the strip 13 and the free edge 25 of the folded portion extends transversely of the strip and is positioned between the strips 12 and 13. The folded end portion of the strip 13 thus forms a second tab 26 which partly supports the shield in position on a foundation garment. Textile stitching 20a binds the marginal edges of the strips 12 and 13 (the right-hand edge viewed in Fig. 1) and also binds the edge 24 of the folded portion 23 to said marginal edge.

A bias tape 27 is sewn to the front edges of the strips and supports apertured halves of snap fasteners 28 which cooperate with headed halves 55 of the snap fasteners which are attached to strips

29 usually secured as by sewing to the front surface of the foundation garment. At the rear of the shield, a strip 30 of elastic material is sewn to the end of each tab 21, 26 and supports an apertured half of a snap fastener 31 which cooperates with a headed half of the snap fastener which is attached to a strip 32 usually secured as by sewing to rear surface of the foundation garment. The snap fasteners and adjoining strips support the shield in its proper position detachably from a foundation garment.

When the shield is attached to a foundation garment worn by a person, the tabs 21 and 26 at the rear of the shield are free to move laterally one relative to the other as required. As an example, when the wearer assumes a sitting position, the back side of the foundation garment gives or stretches circumferentially thus moving the fixed supporting strips 32 further apart. In such position the tabs will move to the position illustrated in dotted lines in Fig. 2, relieving the stress which would otherwise be applied to parts of the shield. This yielding of the tabs provides a more comfortable shield for the wearer than those without yieldable rear portions. As seen in Figs. 1, 2 and 4, the tabs, 21, 26 overlap along part of their length in all relative positions of the tabs providing added comfort for the wearer.

A foundation garment in performing its function of slenderizing the hips and upper thigh naturally press the flesh of the thigh inwardly. Even in the case of women of average build and particularly in stout women, this causes the flesh on the inside of the thighs to rub together in direct contact and chafe. To prevent this direct contact and chafing, chafe preventing portions 11 are attached to each marginal edge of the central strips to depend therefrom and lie between the thighs of the wearer when the shield is being worn. When the wearer is walking the rubbing occurs between the portions 11 and prevents chafing. Each portion 11 has a concavely shaped upper edge 33 to conform to the curvature of the central strips when in worn position. This structure allows the central strips to assume the proper relation to the wearer without causing the chafe preventing portions to gather in folds of excess material.

It is believed apparent from the foregoing that I have perfected a vastly improved detachable shield for a foundation garment. The shield has a shaped construction to eliminate all excess material that might either bulk or be uncomfortable. The novel structure at the rear of the shield allows the wearer a freedom of movement without placing stress on the shield which further adds to the comfort of the wearer.

I claim as my invention:

1. A detachable shield for a foundation garment comprising in combination, two central superposed strips of material extending from front to rear of the shield, said strips being narrowest at an intermediate point and becoming progressively wider in both directions away from the intermediate point, sewing joining said strips along their longitudinal marginal edges from the front to a point just beyond the narrowest portion of the strips, the rear portion of each strip being folded upon itself to form a substantially triangular double layer tab with the base of the triangular tab extending between the longitudinal marginal edges of the strips and the apex thereof positioned near the end of and at the marginal edge of the strip, said tabs being formed on opposite sides of the strips and being adapted to

move laterally relative one to the other to provide a yieldable rear portion of the shield, means at each end of said strips adapted to cooperate with means on the front and back of a foundation garment for removably attaching said strips to the garment and an elongated piece of material sewn to each side of said central strips to depend downwardly therefrom between the thighs of the wearer when the shield is suspended from a foundation garment.

2. A detachable shield for a foundation garment comprising, in combination, a pair of central superposed strips of material extending from front to rear of the shield, said strips being narrowest at an intermediate point and becoming progressively wider in both directions away from the intermediate point, each of said strips terminating in a separate tab disposed at opposite marginal edges of the strips at the rear of the shield, said tabs including the end portion of the strips folded on a bias so that one edge of the folded portion is aligned with the marginal edge of the strip and the free edge thereof extends transversely of the length of the strip, means at the front of the strips and on each tab adapted to cooperate with means on the front and back of a foundation garment for removably attaching said strips to the garment, textile stitching along the longitudinal marginal edges of the strips to bind the strips together and an elongated piece of material sewn to each side of said central strips to depend downwardly therefrom between the thighs of the wearer when the shield is suspended from a foundation garment.

3. A detachable shield for a foundation garment comprising, in combination, a pair of central superposed strips of material extending from front to rear of the shield, said strips being sewn together at their longitudinal marginal edges from the front to an intermediate point of the shield, each strip being folded on a bias from said intermediate point to the rear of the shield forming a substantially triangular shaped tab at the rear of each strip, said tabs being formed at respectively opposite marginal edges of the strips, said tabs being adapted to move laterally relative one to the other to provide a yieldable rear portion of the shield, means for removably attaching the shield to the front and back of a foundation garment and an elongated piece of material sewn to each side of said central strips to depend downwardly therefrom between the thighs of the wearer when the shield is suspended from a foundation garment.

4. A detachable shield for a foundation garment comprising, in combination, a pair of superposed strips of material extending from front to rear of the shield, said strips being narrowest at an intermediate point and becoming progressively wider in both directions away from the intermediate point, the rear portion of each strip being folded on a bias to an opposite longitudinal side of the strips forming a separate supporting tab, textile stitching binding said strips together along the marginal edges thereof and securing an edge of the folded rear portion of each strip to a marginal edge of the strips, and means on the front and on each tab adapted to cooperate with means on the front and back of a foundation garment for removably attaching said strips to the garment, said separate tabs being adapted to move laterally relative one to the other to provide a yieldable rear portion of the shield.

5. A detachable shield for a foundation garment comprising, in combination, a pair of super-

posed strips of material extending from front to rear of the shield, said strips being narrowest at an intermediate point and becoming progressively wider in both directions from the intermediate point, each strip having a rear portion folded on a bias to form a triangular shaped tab with the apex of one of said triangular shaped tabs disposed at one marginal edge of the strips and the apex of the other of said triangular shaped tabs disposed at the opposite marginal edge of the strips, a strip of elastic material attached to each tab and projecting rearwardly of the shield, means at the front of the strips and on each said elastic strip of material adapted to cooperate with means on the front and back of a foundation garment for releasably attaching the strips to the garment, and said tabs being adapted to move laterally one relative to the other to provide a yieldable rear portion of the shield.

6. A detachable shield for a foundation garment comprising, in combination, a central piece of material extending from front to rear of the shield, said piece having a rear portion folded on a bias and becoming progressively narrower toward the rear of the shield, the end of said rear portion being disposed at one of the marginal edges of the piece, an auxiliary piece of material superposed for at least a part of its length over said central piece, said auxiliary piece having a rear portion folded on a bias crossing the bias in the rear portion of said central piece and becoming progressively narrower toward the rear of the shield, the end of the rear portion of said auxiliary piece being disposed at the rear of the shield near the side thereof opposite the end of the rear portion of said central piece, said rear portions being adapted to move laterally of the

shield to provide a yieldable rear portion of the shield and means attached to the front and rear of the pieces for releasably attaching the shield to the front and rear of a foundation garment.

- 5 7. A detachable shield for a foundation garment comprising, in combination, a central piece of material extending from front to rear of the shield, said piece being narrowest at an intermediate point and becoming progressively wider in both directions from the intermediate point, the rear portion of said piece being folded on a bias to form a tab disposed at one marginal edge of the piece, an auxiliary piece of material partially superposed over said central piece and having a rear portion folded on a bias crossing the bias in the rear portion of said central piece and forming a tab disposed at the opposite side of the piece from said first named tab, textile stitching binding said pieces together along their longitudinal marginal edges, means attached to the front of the central piece and to each tab adapted to cooperate with means on the front and rear of a foundation garment for releasably attaching the pieces to the garment, and said tabs being adapted to move laterally of the pieces to provide a yieldable rear portion of the shield.
